UNITED STATES PATENT OFFICE.

ELMER E. PERKINS, OF CHICAGO, ILLINOIS, ASSIGNOR TO ELMER E. PERKINS COMPANY, OF CHICAGO, ILLINOIS, A CORPORATION OF ILLINOIS.

DRYING ROOM.

Application filed April 30, 1924. Serial No. 709,946.

To all whom it may concern:

Be it known that I, ELMER E. PERKINS, a citizen of the United States, residing at Chicago, in the county of Cook and State 5 of Illinois, have invented certain new and useful Improvements in a Drying Room, of which the following is a specification.

This invention relates generally to drying kilns, and while the principles thereof may 10 be embodied in kilns adapted for drying various articles and substances, the invention is illustrated as embodied in a drying kiln which is particularly adapted for drying powdered material employed in the 15 manufacture of confections.

Many confections are dried by surrounding them with powdered material, principally starch, which absorbs the moisture from the confections. In some instances the 20 trays of starch with the confections therein are placed in the drying kiln, and in other instances the moisture is absorbed from the confections by the starch outside the kiln, and the starch in the trays is then placed in 25 the kiln for the removal of the moisture therefrom, so that it may be used again for drying confections.

In drying this powdered material, such as 30 starch, either in conjunction with or separate from the confections, it is desirable that a continuous circulation of air around and between the starch trays be maintained, and that the drying room or kiln be of substantially uniform temperature throughout, and that 35 the circulation of air be not only continuous but substantially uniform. These results are best accomplished by heating the air at the bottom of the kiln beneath the trays, but since the starch is quite inflammable, and 40 since more or less of it is spilled from the trays during the loading and unloading of the kiln, it is essential that provision be made for preventing starch from falling onto the heating pipes.

45 One of the primary purposes of my present invention is to provide a drying room which will have provision for the necessary heating and circulation of the air around the starch trays and which at the same time 50 will afford adequate protection against starch falling on the heating pipes.

In my prior application Serial No. 645,733, filed June 16, 1923, I have disclosed a construction in which tracks are provided upon 55 which truck loads of starch are run into the

drying room. It is advantageous, however, to dispense with fixed tracks, thereby avoiding the possibility of the trucks running off of the tracks and also expediting the loading and unloading of the kiln, and with this 60 end in view my present invention contemplates the provision of a truck supporting structure onto which the trucks may be run in any desired position or relation to each other and which will also afford communication between the space surrounding the heating pipes near the floor and the space 65 above the truck supporting structure in which the starch is dried. The communication thus established provides for adequate 70 circulation of the air from the heating pipes upwardly around the starch trays and back to the pipes again.

Another purpose of the invention is to provide a truck supporting structure of the 75 character indicated, which may be wholly or partially removed in order to afford access to the floor of the room and the space between the heating pipes for the purpose 80 of cleaning out the starch and any other material which may have, during the continued use of the room, accumulated in this space.

Still another object is to provide a truck 85 supporting structure which will not be liable to accidental displacement, one which will be strong and durable and smooth so that the trucks can be trundled about upon it, and also one which will serve to radiate the heat 90 from the pipes beneath it so that the drying of the starch is effected not only by the air which circulates through the structure but also by reason of the heat radiated from the structure.

For the purpose of facilitating an understanding of my invention I have illustrated 95 upon the accompanying drawing a preferred embodiment thereof.

Referring to the drawing,—

Fig. 1 is a transverse sectional view 100 through a drying room embodying my invention.

Fig. 2 is a fragmentary sectional view taken at right angles to the showing in Fig. 1, and

Fig. 3 is a fragmentary detail view showing one of the fasteners for a flat truck supporting member.

Referring to the drawing more in detail, reference character 5 indicates the floor, 6 110

the ceiling, and 7 and 8 the side walls, respectively, of a drying room, any number of which may be assembled in a battery, if desired. Upon the floor of the drying room 5 and projecting upwardly therefrom there is disposed a series of upright standards 9 arranged in rows and comprising a broad base or pedestal adapted to be securely anchored to the floor, and an upright web provided at its upper end with a channel 11 adapted to receive and rigidly support a stringer in the form of a T-bar 12. These T-bars, as will be apparent from Fig. 1, extend transversely of the room and are arranged in spaced relation as shown in Fig. 2.

These stringers are adapted to carry a series of flat truck supporting members 13 preferably formed of sheet metal approximately one-quarter of an inch in thickness 20 and possessing sufficient rigidity so that they will not bend materially between the adjacent stringers. These flat truck supporting members are arranged upon the stringers in spaced relation, as will be apparent from Fig. 1, so as to provide for air circulation between the members. Each member is provided on its lower face with a plurality of angle shaped clips 14 spaced in accordance with the spacing of the stringers so that when the flat member is moved longitudinally in one direction each of the clips will be engaged beneath a flange of each of the stringers, except the endmost 30 stringers, and when the flat member is moved in the opposite direction it will be simultaneously disengaged or disconnected from the stringers so that it may be removed to thereby permit access to the space beneath the structure. In order to hold the 35 flat members against lateral displacement each of them is preferably secured at each end to the underlying stringer by one or more screws 15, as illustrated in Fig. 3. Being rigidly fastened at its ends to the 40 stringers so as to be incapable of lateral or longitudinal movement and being secured to the intermediate stringers by the clips, the flat members are securely anchored so that they will not bend or clatter as the 45 trucks are rolled over them.

The heating pipes are disposed in the space between the truck supporting structure and the floor and while any desired number of pipes may be employed I preferably suspend two pipes by means of hangers 16 directly beneath each flat member 13. The pipes are, therefore, covered by these flat members and any starch or other material falling through the space between the 50 flat members will drop between the heating pipes and lodge on the floor and will not, therefore, come in contact with the heating pipes. For the purpose of maintaining the requisite air circulation the drying room is 55 provided with a condensing coil or coils

which may be arranged in any suitable manner and for illustrative purposes I have shown such condensing coils 17 and 18 as disposed upon the opposite side walls of the room.

It should be apparent from the foregoing that I have provided a drying room comprising a metal truck supporting structure upon which the truck loads of starch trays 19 may be trundled about to any desired position without being restricted by tracks to any definite direction of movement. This flat structure is rigidly supported upon stringers which in turn are carried by rigid standards so arranged as not to interfere with the distribution of the heating pipes beneath the structure. The heating pipes furthermore are covered by the respective flat truck supporting members of the structure so as to prevent starch or other material which may fall through the spaces between the members from lodging upon or coming in contact with the heating pipes. Adequate provision for air circulation is afforded in this construction and at the same time the metal flat members becoming heated up 85 serve to transmit and radiate heat, thereby adding to the efficiency of the room. The structural details illustrated and described may obviously be varied within wide limits 90 without departing from the essence of the invention, as defined in the following claims.

I claim:

1. A drying room comprising heating pipes arranged in spaced relation in proximity to the floor, standards projecting upwardly from the floor above said pipes, stringers supported upon said standards and extending transversely of the pipes, and a plurality of flat members disposed in spaced relation upon said stringers directly over said spaced pipes, whereby material being dried is prevented from falling upon said pipes.

2. A drying room comprising heating pipes arranged in spaced relation in proximity to the floor, stringers arranged in spaced relation above said pipes, and flat truck supporting members disposed upon said stringers in spaced relation and directly over said pipes so as to cover the same.

3. A drying room comprising truck supporting members arranged in spaced relation, stringers upon which said truck supporting members are carried, and heating pipes disposed beneath said members and covered thereby so as to preclude material being dried from falling upon said pipes.

4. A drying room comprising a plurality of standards projecting upwardly in spaced relation from the floor of the room, heating pipes disposed between said standards, stringers carried by the standards, truck supporting members resting upon said string-

ers and disposed directly over said pipes, and means for detachably securing said members to said stringers.

5. A drying room comprising standards arranged upon the floor thereof, pipes disposed between said standards, stringers supported upon the standards, truck supporting members resting in spaced relation upon the stringers, and clips secured to the under-
10 face of said members and adapted to be engaged with said stringers to clamp said members thereto upon longitudinal movement of the members.

6. A drying room comprising standards projecting upwardly from the floor thereof, pipes disposed between said standards,
15

stringers carried by the standards, truck supporting members disposed in spaced relation upon the stringers, clips for detachably securing the members to the intermediate stringers, and means for rigidly fastening the ends of said members to the stringers disposed therebeneath.

7. A drying room comprising truck supporting members arranged in spaced relation 25 above the floor of the room, stringers by which said members are supported, heating pipes extending parallel with and beneath said members, and cooling means in said room remote from said heating pipes.

ELMER E. PERKINS.
